Attorney, Agent, or Firm—Dean W. Russell; Kilpatrick Stockton LLP

[21] Appl. No.: 29/106,360

CLAIM

[22] Filed: Jun. 14, 1999

The ornamental design for an inflatable pool with cover, as shown and described.

[51] LOC (7) Cl. 21-03

DESCRIPTION

[52] U.S. Cl. D21/815

FIG. 1 is a perspective view of an inflatable pool having a cover;

[58] Field of Search D21/815, 816; 4/488, 494, 498

FIG. 2 is an exploded perspective view detailing both the pool and cover of FIG. 1;

[51] LOC (7) Cl. 21-03

FIG. 3 is a side view of the covered pool of FIG. 1, the opposite side being identical thereto (except for omission of the handle, with the region visible because of omission of the handle being ornamented no differently than the regions immediately adjacent thereto);

[52] U.S. Cl. D21/815

FIG. 4 is a plan view of the bottom of the covered pool of FIG. 1; and,

[58] Field of Search D21/815, 816; 4/488, 494, 498

FIG. 5 is a cross sectional view taken along line 5—5 of FIG. 4.
